UNITED STATES PATENT OFFICE.

WILLIS S. MORSE, OF PHILADELPHIA, PENNSYLVANIA.

TENSION-REGULATING MEANS FOR PRINTING-PRESSES.

1,103,153.

Specification of Letters Patent. Patented July 14, 1914.

Application filed March 5, 1912. Serial No. 681,781.

To all whom it may concern:

Be it known that I, WILLIS S. MORSE, a citizen of the United States, residing in Philadelphia, Pennsylvania, have invented 5 certain Improvements in Tension-Regulating Means for Printing-Presses, of which the following is a specification.

One object of my invention is to provide a novel combination of apparatus for automatically regulating the tension on a paper web as it is delivered to a printing press, by regulating the retarding force exerted on the roll of paper from which said web is fed; the construction being such as to maintain the tension of the web substantially 10 constant regardless of the diameter of the paper supply roll and of the other causes which at the present time result in an uneven delivery of the paper through the press or even the breakage of the web.

Another object of the invention is to provide tension regulating means of the above noted general type which shall primarily be relatively simple and substantial in construction, and at the same time relatively 15 sensitive as to its operation; the arrangement of parts being such as to permit of convenient application to a printing press without requiring material alteration of the 20 same.

A further object of the invention is to provide a tension regulating device of the above noted type which shall include electrical apparatus so constructed and arranged as to 25 not require attention or repair for extended periods of time; the device also including novel means for bringing the parts to rest after the current has been cut off from the 30 electrical apparatus.

These objects and other advantageous ends I secure as hereinafter set forth, reference being had to the accompanying drawings; in which,

Figure 1 is a side elevation of a portion 45 of a printing press, illustrating my invention as applied to the rolls on the lower as well as on an upper deck of the machine; Fig. 2 is a sectional plan on the line *a—a* Fig. 1; Figs. 3 and 4 are respectively a front 50 elevation and a plan, partly in horizontal section, of the electric motor and certain of the apparatus immediately associated therewith, employed as part of my invention; Fig. 5 is a front elevation of the reversing 55 switch preferably employed as a part of my invention; Fig. 6 is an enlarged plan, illus-

trating the detail construction of the brake; Fig. 7 is an enlarged side elevation illustrating the detail construction of the preferred form of limit switch, and Fig. 8 is a diagrammatic representation of the electrical apparatus employed as part of my invention.

In the above drawings 1 represents the frame of a printing press of the type commonly employed for newspaper work, and while I have shown this as equipped with two sets of tension regulating apparatus for operation on the paper supply rolls of an upper as well as the lower deck, it is obvious that one or more than two sets of such apparatus may be employed without departing 60 from my invention. The lower roll *X* is mounted on a spindle 2, removably carried in suitable bearings on the frame of the machine and having keyed or otherwise 65 fixed to one end a grooved friction wheel 3. Two brake shoes 4 and 5 are operative on opposite portions of this wheel, and the first of these has fulcrumed to it a lever 6, the second having similarly fulcrumed to it a 70 lever 7.

A pair of threaded sleeves 8 and 9 are respectively pivoted to the two levers 6 and 7, and an oppositely threaded screw 10 engages both of the sleeves, being provided with a 75 hand-wheel 11, whereby the sleeves and hence the levers, may be drawn toward each other or moved apart when desired. The second end of the lever 6 is connected by a link 12 to a rod 13, and a similar link 14 is 80 slotted at its extremity for the reception of a pin 15, carried by the lever 7. The end of this lever adjacent the pin is extended as indicated at 16 and is designed to be engaged by an arm of a lever 17 fulcrumed to the 85 frame of the machine, this lever having a second arm connected by a link 19 to an arm 20. This latter arm is mounted on an oscillatory spindle 21 carried in bearings 90 on the frame and having fixed to it a second arm 22, connected through a link 23, a lever 24 and a link 25 to one end of a screw 26. This latter, shown in Fig. 3, passes through a cross head 27 slidable upon guides 28 carried by suitable brackets mounted on a plate 95 or panel 29, which also serves to support a pair of thrust bearings 30 and 31. Between these latter is mounted the hub of a beveled gear wheel 32, with which meshes a pinion 33 fixed to the armature shaft of a motor 100 34; it being noted that one face of the plate or disk constituting the wheel 32 is flat and

5 forms a braking surface. For the purpose of quickly bringing to rest this plate and the apparatus connected thereto immediately upon the cutting off of current from the motor, I provide a brake, consisting of a stationary arm 35 mounted in the present instance on one of the guide bars 28 and extending over the upper and relatively flat face of the bevel gear 32. To this arm is 10 pivoted a horizontally extending arm 36 having at its outer end a vertical opening in which is mounted a stem 37, carrying at its lower end a brake-shoe 38, in such position as to engage the upper face of the gear 32; there being a spring 39 confined between the arm 36 and the brake-shoe, whereby the 15 latter is at all times forced toward said gear.

As shown in Fig. 6, the arm 36 is provided with a stop 18 placed to be capable of engaging the arm 35 at either extremity of the path of movement of the former, so that the brake shoe is free to swing through an arc of about 180 degrees, in engagement with the bevel gear 32, with the result that the said gear may turn in one of two directions through an arc of about 90 degrees, without having any substantial resistance offered by the brake to its movement.

The cross-head 27 carries an arm 40, on whose free end is mounted a roller 41 designed to engage either of two switch plates 42 and 43 forming part of the limit switch. The construction of these latter is clearly illustrated in Fig. 7 which shows the detail construction of the upper switch. This consists of a pair of collars 44, 45, on the first of which is pivotally mounted the plate or bar 42, which is of such length as to cooperate with a contact formed by a suitably formed part of the collar 45. A spring 47 is so mounted as to at all times tend to hold the bar or blade 42 in contact with said latter collar. Similarly the switch plate 43 is hinged to a collar 44^a and is removably held in engagement with a second collar 45^a by a spring 47^a.

The collars 44 and 45 are adjustably mounted on two terminal structures 48 and 49 carried by a suitable plate 52 of insulating material and provided with suitable binding posts for the attachment of electrical conductors.

The collars 44^a and 45^a are likewise adjustably mounted on two bars 50 and 51 also carried on the plate 52 and having suitable binding posts to which are connected certain electrical conductors hereafter noted; the arrangement of parts being such that the various collars may be fixed at any desired points on their respective bars so that their switch plates 42 and 43 will be engaged and their circuits broken when the arm 40 is moved to either of two predetermined positions. The paper web passing from the roll **X** is carried around a spring supported

roller 55, and thence under a second roller 56, from which it passes over a roller 57 to the parts of the press in which it is operated on. This last roller is rotatably mounted in bearings provided at the ends of a pair of arms 58, fixed to a shaft 59, to which are also fixed arms 60 and 61. The latter of these arms has connected to its end a rod 62, carrying a spring 63 between an abutment on the frame of the machine and an adjustable collar 64, whereby the weight of the roller and its arms is counterbalanced. Said arms 58 are slotted to provide for the adjustable attachment of one end of a rod 65 on which is a second spring 66 operative between an abutment on the frame 1 and the collar 67; the arrangement being such that the roller 57 may be forced against the paper web to give it any desired tension by adjusting said collar on the rod. 70 75 80 85

The arm 60 is connected through a link 68 to the long arm of a lever 69 forming the operating member of the motor reversing switch which is pivoted to a suitable stud, mounted on a plate 70 of insulating material inclosed within a casing 70^a. This lever has a pair of relatively short arms 71 and 72, whose outer ends are preferably curved concentrically with its fulcrum or pivot, and are respectively designed to be capable of engaging contact springs 73 and 74 mounted in suitable positions upon the plate 70. The arrangement of parts is such that when the lever arm 69 is in its mid or neutral position, both of the arms 71 and 72 are disengaged from the spring contacts, although but a relatively short distance, such as a thirty-second to a sixteenth of an inch away from the same, so that a small predetermined movement of the long arm 69 from its mid position will bring one of its short arms into electrical engagement with the adjacent spring contact.

In Fig. 8 I have illustrated the electrical connections of the motor 34, and from this figure it will be seen that the armature 75 has one terminal directly connected to one of the current supply mains, while its second terminal is connected to one of the spring contacts 74 of the reversing switch, as well as to one terminal of a field winding 76. A portion of this winding is mounted on one pole piece 77 of the motor, and a second and equal portion thereof on a second pole piece 78. A second but oppositely wound winding 79 is also provided, and this likewise is wound in two sections, respectively placed on the pole pieces 77 and 78, so that in the event of both of the said windings being simultaneously excited by the same current, they neutralize each other. In order to secure this result the second end of the winding 76 is connected to one end of the winding 79, whose second 120

end in turn is connected to the second spring contact 73 of the reversing switch. The two contact arms 71 and 72 of this switch are connected together and to the 5 point of junction of the two windings 76 and 79 while the second current supply main is connected directly to the line uniting the end of the field winding 79 to the spring contact 73 of the reversing switch.

10 With the above described arrangement of parts, the web from the paper roll X is led around the rollers 55, 56 and 57 as shown, and thence to the printing press in the well-known manner, and the proper tension is 15 given to said web by manipulating the hand-wheel 11, until the levers 6 and 7 are caused to press the brake-shoes 4 and 5 into engagement with the friction wheel 3 with the requisite force. Under these conditions the 20 roll 57 assumes a definite position, corresponding to and depending upon a certain definite and predetermined tension of the web Y and the various parts are then so adjusted that the cross-head 27 is in a position with its roller 41 midway between the 25 two switch-plates 42 and 43, and the arm 69 of the reversing switch is likewise in its mid or neutral position. If current be now supplied to the motor, it will be noted that 30 while there is a flow through its armature and both of the field coils, there is no revolution of said armature, because said two coils are designed to completely neutralize each other.

35 When for any of the various reasons well known in this particular art, there occurs a variation in the tension of the web Y, it is obvious that the position on the roller 57 is instantly changed, and assuming that it 40 is slightly lowered by an increase of the web tension the arms 58 and 60 are so moved that the arm 69 of the reversing switch is thrown from its mid position to such a position that the arm 71 electrically engages the 45 spring contact 73. As a result the field-winding 79 is short-circuited and the motor 34 at once starts to turn the bevel gears 33 and 32 in such a direction as to move the screw 26 downward. There is thus a downward pull on the link 25 which is transmitted through the medium of the lever 24, link 23, lever 20, link 19 to the arm of the lever 17 so that this is moved away from the extension 16 of the lever 7, thereby permitting 50 this latter and the lever 6 to so move as to slack off the brake-shoes 4 and 5 from the grooved wheel 3. The paper roll X is consequently free to turn with greater freedom than heretofore, and the tension of the web 55 Y is diminished sufficiently to allow the roll 57 to return to its normal position. If the lessening of the retarding force on the roll X is more than was necessary to bring the tension to normal, the roll 57 through the 60 medium of the arms 58, 60 and 69 causes the

contact 72 to engage the spring contact 74 of the reversing switch, thereby short-circuiting the winding 76 of the motor field, and making effective the winding 79. As a consequence the motor is at once started in the 70 direction opposite to that heretofore noted and through the levers and links connecting the screw 26 with the lever arm 17, an upward pressure is exerted on the extension 16 of the lever 7, thereby increasing the retarding force exerted by the brake-shoes 4 and 5 on the grooved friction wheel 3, and correspondingly increasing the tension on the paper web. With this arrangement of parts therefore, the web tension is maintained practically uniform, being instantly brought to normal if it is increased or diminished owing to the various causes occurring under operating conditions, particularly as the size of the paper roll diminishes. 75 80 85

By the particular motor controlling device above described the motor is at all times ready to instantly start in either direction with but a minimum throw of the movable member of the reversing switch, and it is 90 particularly to be noted that the engagement and disengagement of the contacts 72-74 and 71-73 is unaccompanied by injurious sparking or arcing in view of the peculiar arrangement of windings and connections 95 employed. The instantaneous starting of the motor is in no way interfered with by reason of the brake, since, if the arm 36 be in a position mid-way between its two extreme positions when the arm 69 of the 100 reversing switch is likewise in its mid position, the turning of the gear 32 is in no wise retarded by the brake, as the arm is being swung toward either one of its extreme positions. As a consequence it is not until 105 after the motor is well started that the brake comes into action, and although it thereafter continuously exerts a retarding force upon the gear 32 sufficient to instantly stop its movement when current is cut off from the 110 motor, such retardation is not objectionable in view of the construction and arrangement of parts employed. As soon as the motor is started in the opposite direction the arm 36 is swung on its pivot, by reason of 115 the engagement of the shoe 38 with the gear 32, until it is brought to rest by engagement with one of its stops, so that as before the motor has full opportunity to start without hindrance from the brake. 120

From Fig. 6 it will be noted that when the brake shoe 38 is in the position shown in full lines and the gear is turning in the direction indicated by the arrow, the retarding force exerted is materially greater 125 than when the gear is turned in the opposite direction and said shoe is in the position shown in dotted lines; in view of the fact that the shoe is acting at a greater distance from the screw 26 in the first case than in 130

the second. Such an arrangement is employed because the load on the motor is much less when the friction on the grooved wheel 3 is being removed than when it is being applied and hence the force necessary to prevent "drifting" of the motor and of its attached parts is required to be greater in the former case than it is in the latter case. If for any reason the roll 57 should move so far in either direction as to maintain either of the contacts 71 or 72 in engagement with its adjacent spring contact for such a length of time as would cause the motor to operate the screw 26 until this had moved too far in either direction through the hub of the gear wheel, the roller of the arm 40 would engage one or the other of the switch plates 42 or 43 and by moving them away from their contacts 45 or 45^a, break the current supply of the motor, thereby bringing this to rest before any part of the device could be injured. Any excessive movement of the roll 57 is of course prevented by the springs 63 and 66. With the above arrangement of parts the variation of the tension of the paper web Y is automatically restricted to exceedingly narrow limits, so that it is practically constant, particularly since any serious variation in the tension is at once compensated for by the above described automatic device. Not only is said device extremely sensitive, but it is likewise rapid in its action, responding instantaneously to any alteration in the tension of the web.

As shown in Fig. 1, a second and substantially similar apparatus is applied to the roll and web of the lower deck of the press and this is designed to operate as above described, it being immaterial how many of such sets are employed as each is designed to independently regulate the tension of its particular web.

I claim—

45 1. In a tension regulating device for printing presses, the combination of a pivotally mounted member operative on the paper web; braking mechanism operative on the paper supply roll; a normally idle motor connected to said mechanism for varying the retarding force exerted thereby; controlling mechanism for the motor governed by said pivotally mounted member, said mechanism comprising a reversing switch automatically controlled by said pivotally mounted member and a retarding device for the motor and its associated mechanism including means whereby said device is prevented from being operative until after the 60 motor has moved to a predetermined extent.

2. In a tension regulating device for printing presses, the combination of a pivotally mounted member operative on the paper web; braking mechanism operative on the paper supply roll; a normally idle motor

connected to said mechanism for varying the retarding force exerted thereby; controlling mechanism for the motor governed by said pivotally mounted member, said mechanism comprising a reversing switch 70 automatically controlled by said pivotally mounted member and retarding apparatus for the motor and its associated mechanism; said apparatus including a device for exerting a greater retarding force when the motor moves in one direction than when it moves in the opposite direction. 75

3. In a tension regulating device for printing presses, the combination of a movable member operative on the paper web; braking mechanism operative on the paper supply roll; a motor connected to said mechanism for varying the retarding force exerted thereby; controlling mechanism for the motor governed by said movable member; with 80 retarding apparatus for the motor and its associated mechanism; the same including a device for exerting a greater retarding force when the motor moves in one direction than when it moves in the opposite direction; said means being arranged to be inoperative until the motor has moved to a predetermined extent. 90

4. In a tension regulating device for printing presses, the combination of braking mechanism operative on the paper supply roll; a motor connected to said mechanism for varying the retarding force exerted thereby; controlling means for the motor governed by the paper web; means for connecting the motor with said braking mechanism including a rotary disk; and a device for retarding the rotation of the disk including a movable supporting structure; a brake shoe carried thereby in engagement 105 with the disk and free to move with the supporting structure toward and from the center of the disk.

5. In a tension regulating device for printing presses, the combination of braking 110 mechanism operative on the paper supply roll; a motor connected to said mechanism for varying the retarding force exerted thereby; means governed by the paper web for controlling the motor; means including 115 a gear for connecting the motor with the braking mechanism; and a device for braking the motor, the same including a brake shoe frictionally engaging said gear.

6. In a tension regulating device for printing presses, the combination of a movable member operative on the paper web; braking mechanism operative on the paper supply roll; a motor connected to said mechanism for varying the retarding force exerted thereby; controlling means for the motor governed by the movable member; a retarding device operative on the motor and including means whereby the retarding force exerted is greater when the motor operates 120 125 130

to slack off the braking mechanism than when it is operating to apply said mechanism.

7. The combination in a tension regulator for printing presses of a pivotal member having its free end supported on the sheet and made sensitive to variations in the tension of said sheet; a spring mounted to resist movement of said member under the action of the sheet in one direction; a second spring operative on the pivoted member to press it against the sheet with a definite force; a current-controller; connections between said pivoted member and the current-controller, said connections responding to movements of said member and including a member occupying a neutral position relative to the current-controller as long as the sheet is under proper working tension; and movable in one of two directions away from neutral in response to sheet-tension changes; mechanism including a normally idle electric-motor in circuit with the current-controller and made active by and quickly responding to the movement of the second-named member from its neutral position; and connections between the motor and the roll which supplies the sheet for controlling the revolution of said roll.
8. The combination in a tension regulator for printing presses of a pivoted member having its free end supported on the paper sheet and made sensitive to variations in the tension of said sheet, two springs operative on the pivoted member to oppose movement of the free end thereof from a predetermined position, one of said springs being mounted to counterbalance the weight of the member and the other being connected to said member to cause it to exert greater or less tension on the paper web; a current-controller; connections between said pivoted member and the current-controller, said connections responding to movements of said member and including a member occupying a neutral position relative to the current-controller as long as the sheet is under proper working tension, and movable in one of two directions away from neutral in response to sheet tension changes; mechanism including a normally idle electric motor in circuit with the current-controller and made active by and quickly responding to the movement of the second-named member from its neutral position; and connections between the motor and the roll which supplies the sheet for controlling the revolution of said roll.

9. In a tension regulating device for a printing press, the combination of a movable member operative on the paper web; braking mechanism operative on the paper supply roll; a normally idle electric motor connected to said mechanism for varying the retarding force exerted thereby; controlling mechanism for the motor governed by said

movable member, and an automatically acting device for opening the circuit of the motor after it has operated the braking mechanism to a predetermined extent in either direction.

10: In a tension regulating device for a printing press, the combination of a movable member operative on the paper web; braking mechanism operative on the paper supply roll; a motor for varying the retarding force exerted by said mechanism; controlling mechanism for the motor governed by said movable member; means for connecting the motor with the braking mechanism; the same including a screw; a cross-head operative thereon; and two switches in circuit with the motor placed to be respectively opened by said cross head after it has been moved a pre-determined distance in either direction.

11. In a tension regulator for a printing press or the like, the combination of a web-roll shaft, braking mechanism for retarding or permitting the acceleration of said shaft, driving mechanism for operating said braking mechanism to vary the retarding force exerted thereby, controlling means for the driving mechanism and governed by variations in the tension of the web, and retarding means for the driving mechanism.

12. In a tension regulator for a printing press or the like, the combination of a web-roll shaft, braking mechanism for retarding or permitting the acceleration of said shaft, driving mechanism for operating said braking mechanism to vary the retarding force exerted thereby, controlling means for the driving mechanism and governed by variations in the tension of the web, and a device for retarding the driving mechanism including means whereby said device is prevented from being operative until after the driving mechanism has operated to a predetermined extent.

13. In a tension regulator for a printing press or the like, the combination of a web-roll shaft, braking mechanism for retarding or permitting the acceleration of said shaft, driving mechanism for actuating said braking mechanism to vary the retarding force exerted thereby, controlling means for said driving mechanism, a member movable in response to variations in the tension of the web, and arranged to cause the operation of said controlling means when the tension of the web varies above or below normal, and automatic means for preventing the operation of the braking mechanism by said driving mechanism after the latter has actuated the braking mechanism to a predetermined extent in either direction.

14. In a tension regulator for a printing press or the like, the combination of a web-roll shaft, braking mechanism for retarding or permitting the acceleration of said shaft,

driving mechanism for actuating said braking mechanism to vary the retarding force exerted thereby, controlling means for said driving mechanism, and governed by variations in the tension of the web above or below normal or working tension, and means for preventing the operation of the braking mechanism by the driving mechanism after the latter has actuated the braking mechanism to a predetermined extent.

15. In a tension regulator for a printing press or the like, the combination of a web-roll shaft, braking mechanism for retarding or permitting the acceleration of said shaft, a normally idle and energized electric driving mechanism for operating said braking

mechanism to vary the retarding force exerted thereby, and controlling means governed by variations in the tension of the web and arranged to cause the operation of the driving mechanism to actuate the braking mechanism when the tension of the web varies above or below normal or working tension.

In testimony whereof, I have signed my name to this specification, in the presence of two subscribing witnesses.

WILLIS S. MORSE.
